DESIGN FOR A PULL FOR SLIDE FASTENERS

Alfred E. Carlile, Meadville, Pa.

Application July 12, 1933. Serial No. 48,699

Term of patent 14 years

To all whom it may concern:

Be it known that I, ALFRED E. CARLILE, a citizen of the United States, residing at Meadville, in the county of Crawford and State of Pennsylvania, have invented a new, original, and ornamental Design for Pull for Slide Fasteners, of which the following is a specification, reference being had to the accompanying drawing, forming a part thereof.

In the drawing:

Fig. 1 is a plan view of a pull for slide fasteners showing my new design;

Fig. 2 is a side view of the same.

I claim:

The ornamental design for a pull for slide fasteners as shown.

In testimony whereof I affix my signature.

ALFRED E. CARLILE.
